Swank, Inc., Attleboro, Mass., a corporation of Delaware

Filed Mar. 10, 1965, Ser. No. 84,178

Term of patent 14 years

(Cl. D34—5)

FIGURE 1 is a front elevational view of an alphabet dart game board or similar article, showing my new design;

The dominant features of my design reside in the portions shown in full lines.

The drawing is lined to indicate contrasting colors.

I claim:

The ornamental design for an alphabet dart game board, or similar article, as shown and described.
